UNITED STATES PATENT OFFICE.

LOUIS VOYE, OF McDONALD, PENNSYLVANIA.

DESIGN FOR AN AUTOMOBILE-SIGNAL.

59,444.

Specification for Design.

Patented Oct. 18, 1921.

Application filed April 26, 1921. Serial No. 464,696. Term of patent 3½ years.

To all whom it may concern:

Be it known that I, LOUIS VOYE, a citizen of the United States, residing at McDonald, in the county of Washington and State of Pennsylvania, have invented a new, original, and ornamental Design for Automobile-Signals, of which the following is a specification, reference being had to the accompanying drawings, forming a part hereof.

The figure is a front elevation showing my new design.

I claim:

The ornamental design for an automobile signal as shown.

LOUIS VOYE.
